HYDROCARBON BLAST BURNER.

1,404,429.

Specification of Letters Patent. Patented Jan. 24, 1922.

Application filed March 14, 1918. Serial No. 232,453.

To all whom it may concern:

Be it known that we, WILLIAM C. BUELL, Jr., and WALTER H. SCHEIB, citizens of the United States, and residents of Osborne 5 Borough, Allegheny County, Pennsylvania, and Pittsburgh, Allegheny County, Pennsylvania, respectively, have invented a new and useful Improvement in Hydrocarbon Blast Burners, of which the following is a full, 10 clear, and exact description, reference being had to the accompanying drawings, forming part of this specification, in which—

Figure 1 is a longitudinal vertical section showing a liquid fuel burner constructed in 15 accordance with our invention, and

Figure 2 is a side elevation of the same.

Our invention relates to the blast burners for liquid hydrocarbon fuels wherein a fluid, such as steam or air is employed as an atomizing agent. In such systems, it is important for efficient atomization that the atomizing agent be maintained at a high velocity 20 at the meeting point with the fuel from the nozzle, inasmuch as velocity has a direct 25 atomizing function. Velocity is a function of pressure drop and frictional resistance. If the pressure of the atomizing agent is varied by a remote valve control the efficiency of atomization will be greatly reduced 30 as the pressure is reduced.

Furthermore, the velocity of the atomizing fluid has an important effect on the proportion of secondary air induced for combustion; and we have found that by the use 35 of our invention a very large proportion of the total air can be induced by the action of a relatively small amount of primary air flowing through the burner tip.

Our experiments have shown that it is 40 highly desirable that the static head of air, steam or other atomizing agent be maintained at a high point to the meeting point of the fuel and atomizing agent, so that maximum velocity and consequently highly 45 efficient atomizing and inductive action for secondary air be secured.

In our invention the static head of the atomizing agent is maintained substantially constant at the nearest practical point in a 50 burner tip so as to give a condition of almost constant velocity, while at the same time the volume of the atomizing agent may be varied at will. Furthermore, all sliding internal fittings are obviated with the excep-

tion of a fitting which is packed only against 55 low pressure air. Furthermore, in our burner the amount of air supply is indicated by the position of an externally projecting control lever.

In the form shown in the drawings, 2 is 60 the outer shell or casing of the burner having in its rear portion a cylindrical bore 3. The rear end is closed by a hollow cap 4 to which the oil or other liquid fuel is admitted through the pipe 5. Within the 65 cylindrical bore 3 fits the hollow enlarged hub 6 of a sleeve 7 carrying a tip 8 at its forward end. 9 represents a suitable packing for the hub which turns and slides in the bore. The hub is actuated by a lever 70 handle 10 having its inner end secured into the hub and projecting through a helical slot 11 in the outer shell or casing. By actuating the handle, the tip may be moved forwardly or backwardly as the hub turns 75 around within the bore.

Through the hollow hub and sleeve extends an inner tube 12 having its rear end screwed into the rear hollow cap for the oil feed, while to its forward end is screwed 80 the fuel tip 13, which projects through the outer tip with its forward end practically flush with the hole in the burner casing. The usual needle valve 14 controls the flow 85 of liquid through to the fuel tip, the rear end of the needle stem being screw threaded and extending through the rear cap with an actuating handle 15.

With the parts in the position shown, when the lever is actuated to turn the hub 90 of the outer tip, this tip is moved forwardly over the stationary fuel tip, thus reducing the effective area of the hole in the outer burner shell, and throttling the volume of flow of the atomizing agent at the point 95 where the atomizing agent and the fuel join in the atmosphere.

The opening for the atomizing agent can be varied from closed to full open position with a lever handle movement of about 120°, 100 thus giving quick action and also optical indication as to the position of the parts. At the same time the velocity of flow of the atomizing agent is held substantially uniform, because the pressure on the inside of 105 the external burner shell remains uniform under the supply from the duct 16 for the primary pressure air, while the atmospheric

pressure, of course, remains the same at the opening of the burner assembly.

It will be understood that the maximum opening of the annular nozzle between the shell 2 and the tip 8 is small compared to the cross sectional area of duct 16 so that the line pressure is maintained in the conduit 16 even with the maximum useful opening between the shell 2 and tip 8.

10 We have shown the assembly projecting into a hole in the wall of a combustion chamber, as in the usual manner.

The advantages of our invention result from the use of the intermediate tip which 15 may be adjusted relative to the shell and the fuel tip while the device is in use. The static head of the atomizing agent is thus maintained substantially constant so as to give a condition of almost constant velocity 20 under varying volume of the atomizing agent as changed by the operator.

The enlarged hub bearing keeps the tip 6 concentric with the outer nozzle or burner shell and this tip also acts as a guide for 25 the fuel tip, thus maintaining the three in concentric position.

Changes may be made in the form and arrangement of the parts without departing from our invention.

30 We claim:

1. In liquid fuel blast burners, a casing having a side inlet for the atomizing fluid and provided with a gradually contracting outlet, a stationary axially located fuel supply tube within the casing provided with a central longitudinal needle valve adjacent to the fuel outlet, and an intermediate con-

centric sliding sleeve between the casing and fuel tip and having a throttle tip between the fuel tip and the casing, the rear portion 40 of said intermediate sleeve having packing in the rear of the casing inlet and provided with operating means in the rear of said packing, substantially as described.

2. In liquid fuel blast burners, a hollow 45 burner shell having a nozzle and containing a bore in its rear portion, a sliding hub within the bore having an actuating handle projecting through the burner shell, the hub having a member provided with a front 50 throttling tip co-acting with the hole in the burner shell, a stationary oil supply extending through the hub and throttling tip and provided with a fuel tip extending through the throttling tip to the point where the 55 atomizing fluid and the oil combine, and a needle valve for the fuel tip; substantially as described.

3. In a liquid fuel burner, an outer casing, an inner stationary fuel supply tube, 60 an intermediate tube between the casing and the supply tube adjustable longitudinally of the casing, a packing between the casing and the intermediate tube, the casing having a helical slot on the atmospheric pressure side of the packing, and a handle connected to the intermediate tube and movable in the helical slot of the casing, substantially as described.

In testimony whereof, we have hereunto 70 set our hands.

WILLIAM C. BUELL, JR.
WALTER H. SCHEIB.
